DOORCHECK

Application filed March 5, 1928. Serial No. 259,263.

This invention is an improvement in door checks, and more particularly in checks for doors of light weight.

The useful construction of door check is designed more particularly for heavy doors, and the force which operates to close the door, as well as the braking force, are relatively large, so that the check is hardly suitable for doors of light weight, such for instance as screen doors.

Such checks are also relatively expensive, making use of fluid driven from one chamber to another through a restricted opening, and with a by-pass for purposes of adjustment. Such checks offer considerable resistance to the opening movement of the door, as well as a braking resistance to the closing thereof.

One of the primary objects of the present invention is the provision of a simple, inexpensive check, capable of use with any type of door, but particularly designed for doors of light weight.

Another object is the provision of a check wherein fluids and liquids are dispensed with, springs being relied upon to provide the required resistance.

With these and other objects in view the invention consists in the construction and novel combination of parts fully described hereinafter, illustrated in the accompanying drawings, and pointed out in the claims appended hereto, it being understood that various changes in the form, proportion, size and minor details of construction within the scope of the claims, may be resorted to without departing from the spirit of the invention.

In the drawings forming a part hereof:—

Fig. 1 is a front elevation of a part of a door and its framing, provided with the improved check.

Figs. 2 and 3 are enlarged sections taken on the lines 2—2 and 3—3 respectively, of Fig. 1.

Figs. 4 and 6 are sections taken on the lines 4—4 and 6—6 respectively of Fig. 3.

Fig. 5 is a view similar to Fig. 4 showing the parts in another position.

The present embodiment of the invention

is shown in connection with a door 1, mounted in the frame 2, both of usual construction, and the improved check is arranged between the door and the framing at the top. The check comprises a case 3 of substantially cylindrical form, having a base 4 by means of which it may be secured to the door, and within the case is mounted a spring 5, one end of the spring being connected to the case, and the other to a shaft 7 (Fig. 6), which shaft is journaled at the axis of the case.

A head 9, in the form of a peripherally grooved wheel, is pinned or otherwise secured to the top of the shaft 7, the said shaft extending well above the case 4, and a metallic ribbon 10 is arranged in the groove to wind upon the wheel.

The ribbon is secured to the wheel at one end by the pin 8 which connects the wheel to the shaft, and the other end is connected to a bracket 11 which is secured to the door frame in any suitable manner. The spring 5 is arranged to wind up the ribbon 10 on the wheel, and it will be apparent that when the door is opened, the ribbon will be withdrawn from the wheel, and the shaft 7 will be rotated in a direction to put the spring 5 under tension, that is, to cause the spring to assist the closing movement of the door.

A slotted arm 13 is pivotally connected at one end to a bearing lug 14 secured to the door frame on the opposite side of the case 3 from the connection of the ribbon 3, and the shaft 7 passes through the slot 15 of the arm. A brake disk 16 is journaled on the shaft just above the arm, and the disk has a pair of arc shaped tongues 17, struck up from the material of the disk, and upwardly bent as shown more particularly in Fig. 3, so that the free ends of the tongues lie above the plane of the disk.

The free end of each tongue is provided with a lip 18, and pins 19 mounted in the head cooperate with the tongues. These pins are vertically adjustable in the head, and they are arranged at radial distances from the axis of the shaft, corresponding to the distance at which the tongues 17 are spaced from the said axis. It will be

noticed referring to Figs. 3, 4 and 5, that the tongues are arc shaped longitudinally, being formed on arcs coaxial with the shaft 7.

During the rotation of the shaft 7 in either direction, the pins 19 move in a circle in which the tongue 17 are arranged, and some time during the rotation of the head they will contact with the tongues. When the wheel is moving under the influence of the spring, (that is during the closing of the door) the pins will engage the tongues at their connection with the disk, and will move up on the higher parts of the tongues (Fig. 4). Since the tongues are resilient, an increasing pressure will be brought to bear upon the disk 16, and thus a braking action will be exerted on the rotation of the shaft, that is upon the stress which tends to close the door.

When the ribbon 10 is unwinding, that is when the door is opening, the pins will move toward the lips 18, as shown in Fig. 5, and will engage the lips, and will cause the disk to rotate clockwise, so that there is no downward pressure on the disk, and no braking tendency.

Thus no opposition is offered to the opening of the door, except the increasing tension of the spring 5, but when the door is released, and the full force of the spring acts to close the same, the engagement between the pins 19 and the tongue 17 takes place at an early stage of the closing movement, and gradually exerts an increasing braking action on the closing movement, so that the door is tightly and efficiently closed, without however, any slam or jar.

The improved check is simple and inexpensive. No regulation is required other than the setting of the pins 19, and the pins, as clearly shown in Fig. 3, have threaded engagement with the head, in order to enable vertical adjustment. Preferably a washer 20 is arranged in the casing above the spring 5, as shown in Fig. 3. The check may be also utilized to serve as a scotch to hold the door open, by adjusting the brake screws to provide more friction than the spring will overcome, in which case the door will stand substantially at the position in which it is placed, while at the same time it may be moved to open or closed position.

What is claimed as new is:—

1. A door check including a shaft, a spring connected with the shaft to rotate it in one direction, a flexible member having at one end means for connection with the door frame and connected at the other to the shaft to be unwound therefrom when the door is opened, thereby to tension the spring, and to be wound thereon by the spring thereby to close the door, a slotted guide arm having means for pivotal connection

with the frame, the shaft passing through the slot, a brake disk loosely mounted on the shaft and resting on the arm, and means in connection with the shaft and the disk cooperating to press the disk toward the arm when the shaft is rotated under the influence of the spring, and inoperative to exert pressure when the shaft is rotated under the influence of the flexible member.

2. A door check including a shaft, a spring connected with the shaft to rotate it in one direction, a flexible member having at one end means for connection with the door frame and connected at the other to the shaft to be unwound therefrom when the door is opened, thereby to tension the spring, and to be wound thereon by the spring thereby to close the door, a slotted guide arm having means for pivotal connection with the frame, the shaft passing through the slot, a brake disk loosely mounted on the shaft and resting on the arm, means in connection with the shaft and the disk cooperating to press the disk toward the arm when the shaft is rotated under the influence of the spring, and inoperative to exert pressure when the shaft is rotated under the influence of the flexible member.

3. A door check including a shaft, a spring connected with the shaft to rotate it in one direction, a flexible member having at one end means for connection with a door frame and connected at the other to the shaft to be wound thereon when the shaft is rotated by the spring, thereby to close the door, and to be unwound therefrom when the door is opened, thereby to tension the spring, a slotted guide arm having means for pivotal connection with the frame, the shaft passing through the slot, a brake disk loosely mounted on the shaft and resting on the arm, and means in connection with the shaft and the disk cooperating to press the disk toward the arm when the shaft is rotated under the influence of the spring, and inoperative to exert pressure when the shaft is rotated under the influence of the flexible member, said last named means including a wheel secured to the shaft upon which the flexible member winds, pins connected to the wheel and axially adjustable thereof, the disk having arc shaped resilient tongues inclining upwardly from the face thereof and in the line of movement of the pins.

4. A door check including a wheel having means for rotatably connecting it to a door, a flexible member connected to the wheel at one end to wind thereon, and having means at the other end for connection with a door frame, a spring acting normally to rotate the wheel in a direction to wind up the flexible member, a brake disk mounted coaxial with the wheel and movable axially

with respect thereto, a member having means for pivotal connection with the frame, slideable with respect to the disk and with which the disk cooperates, and pins connected with the wheel and axially adjustable thereof, the
5 disk having arc shaped resilient tongues inclining upwardly from the face thereof and in the line of movement of the pins to be engaged thereby.

Signed at Gastonia, in the county of Gaston and State of North Carolina this eighth day of February, A. D. 1928.
